UNITED STATES PATENT OFFICE.

ALBERT F. HASKINS AND THOMAS B. COX, OF KINSTON, NORTH CAROLINA.

SHELL-CRIMPER.

SPECIFICATION forming part of Letters Patent No. 372,466, dated November 1, 1887.

Application filed July 11, 1887. Serial No. 243,960. (No model.)

To all whom it may concern:

Be it known that we, ALBERT F. HASKINS and THOMAS B. COX, of Kinston, in the county of Lenoir and State of North Carolina, have 5 invented certain new and useful Improvements in Shell-Crimpers; and we do hereby declare the following to be a full, clear, and exact description of the same, reference being had to the accompanying drawings, forming a part of 10 this specification, and to the figures and letters of reference marked thereon.

The object of the present invention is to produce a shell-crimper adapted to crimp any 15 number of shells at one operation; and to this end it consists in the arrangement and combinations of parts and details of construction, to be hereinafter described, and pointed out particularly in the claims at the end of this specification.

20 In the accompanying drawings, Figure 1 is a perspective view of a crimper constructed in accordance with our invention. Fig. 2 is a sectional view of the same. Fig. 3 is an end view.

25 Similar letters of reference in the several figures indicate the same parts.

The operative parts of the crimper are mounted upon a base, A, adapted to be secured to a table or other support by a clip, a, 30 and thumb-screw b, as shown. Rising from this base are two upright portions or frames, one, B, having openings therein, in which are secured light barrels B', constituting guides for and supporting the shells while being 35 crimped, the other, C, serving as a support for the crimper-heads, as will now be explained.

A number of rotary heads corresponding 40 to the guides or supports in the upright B have their bearings in the upright C and constitute the turning or crimping part of the apparatus. They are so constructed with grooves c and beveled lugs c' in them as that they will, when brought into engagement with the edge of a shell, turn and crimp the same. 45 In order to rotate these heads, we mount on the rear end of their shafts, extended through the upright C, small gear-wheels D, which are driven from a relatively large gear-wheel, D', located in the center and engaging the whole 50 series of said wheels D. The gear-wheel D' in turn receives motion from the crank and handle D², mounted on its shaft. We prefer-

ably support the shaft of the larger gear-wheel, D', in two bearings, one in the upright C and the other in the end of standard E, rising from 5 the base-piece. The shells, having been placed in the barrels B', are forced into the crimper-heads by the forward movement of the plate or section F, having U-shaped pieces thereon, provided with suitable means for engaging the 60 heads of the shells and preventing their rotation.

The movable section F takes its bearing in the slots formed by the clips G, and is moved forward or backward by the hand-lever H, 65 hinging on the base-piece and connected to said section F by the two arms or link-connections I. It will thus be seen that the section F will be drawn out or moved longitudinally at both top and bottom simultaneously. 70

In order to strengthen the uprights B and C, they are provided at their bases with braces or supports K.

The operation of crimping the loaded shells is as follows: A number are taken by the operator and inserted in the barrels B'. The section F is then moved up, forcing the shells into the crimping-heads, when the crank D² is turned and the edge of the shell turned in 75 upon itself or crimped. 80

We do not wish to be limited to the number of crimpers that may be embodied in one machine, as it is obvious that they may vary from two to as many as can be placed around the central driving-wheel, which latter may 85 be of any desired size.

It is obvious that the machine may be run by power, the crimper-heads being constantly in motion, as they will only operate upon the shells when the latter are forced in against 90 them.

Having thus described our invention, what we claim as new is—

1. In a shell-crimper, the combination, with 95 two or more guides or supports for the shells and rotary crimper-heads corresponding thereto, having their bearings in a fixed frame and driven by a common power, of bearings for engaging the bases of the shells, preventing their rotation, and forcing them inward 100 against the crimper-heads, substantially as described.

2. In a shell-crimper, the combination, with 105 two or more guides or supports for the shells

- and rotary crimper-heads corresponding thereto, having their bearings in a fixed frame and driven by a common power, of bearings for engaging the bases of the shells, operated by a single lever for forcing the shells inward against the crimper-heads, substantially as described.
3. In a shell-crimper, the combination, with the guides for the shells and the movable section for forcing them inward, of the series of rotary crimper-heads mounted in a fixed frame, and having gear-wheels thereon, all of which derive motion from an intermediate gear-wheel, substantially as described.
- 15 4. The combination, with a shell-crimper provided with two or more rotary crimper-heads and guides corresponding therewith, of a movable plate or section for forcing said shells into the rotary crimpers, connected to a lever or equivalent device by two or more link-connections, whereby it is moved longitudinally at top and bottom simultaneously, substantially as described.
5. The combination, with a shell-crimper provided with two or more rotary crimper-heads and guides corresponding therewith, of a movable plate or section for forcing said shells into the rotary crimpers having its bearings in slots and connected to a lever or equivalent device by two or more link-connections, whereby it is moved longitudinally at top and bottom simultaneously, substantially as described.

ALBERT F. HASKINS.
THOMAS B. COX.
